UNITED STATES PATENT OFFICE

147,718

DESIGN FOR A PLAYING CARD HOLDER

George B. Brady, Stamford, Conn.

Application July 16, 1946, Serial No. 131,604

Term of patent 3½ years

(Cl. D34—5)

To all whom it may concern:

Be it known that I, George B. Brady, a citizen of the United States, residing at Stamford, in the county of Fairfield and State of Connecticut, have invented a new, original, and ornamental Design for a Playing Card Holder, of which the following is a specification, reference being had to the accompanying drawing, forming a part thereof.

I claim:

The ornamental design for a playing card holder, as shown.

GEORGE B. BRADY.
